Des. 177,162
Patented Mar. 13, 1956

177,162

COMBINED HOT DOG MACHINE AND DRINK DISPENSER

Samuel M. Waas, Kansas City, Mo., assignor to Manley,
Inc., Kansas City, Mo., a corporation of Missouri

Application November 2, 1955, Serial No. 38,705

Term of patent 14 years

(Cl. D81—10)

Fig. 1.

Fig. 2.

Fig. 1 is a front perspective view of a combined hot dog machine and drink dispenser, showing my new design; and

Fig. 2 is a rear perspective view of the combined hot dog machine and drink dispenser.

I claim:

The ornamental design for a combined hot dog machine and drink dispenser, as shown.
